UNITED STATES PATENT AND TRADEMARK OFFICE
CERTIFICATE OF CORRECTION

PATENT NO. : Des. 526,656 S
APPLICATION NO. : 29/228365
DATED : August 15, 2006
INVENTOR(S) : Charles W. Stabb et al.

It is certified that error appears in the above-identified patent and that said Letters Patent is hereby corrected as shown below:

TITLE PAGE
DESCRIPTION,

“The broken line showing of various regions and the unshaded areas there within form no part of the claimed design. The broken line showing of the display screen is for illustrative purposes only and forms no part of the claimed design.”

has been replaced with:

--The broken line drawing of rectangles and circles and the areas within them are not part of the claimed design. The broken line drawing of the display screen is for illustrative purposes only and forms no part of the claimed design.--

Signed and Sealed this

Twenty-third Day of January, 2007
